[57] **CLAIM**

The ornamental design for a mobile cart for electrosurgical instruments and accessories therefor, as shown and described.

DESCRIPTION

FIG. 1 is a perspective view of a mobile cart for electrosurgical instruments and accessories therefor, the left side of the cart being identical to the right side as shown.

FIG. 2 is a rear view of the cart of FIG. 1;

FIG. 3 is a bottom view of the cart of FIG. 1;

FIG. 4 is a view similar to FIG. 1; the broken line showing of the electrosurgical instrument on the top shelf, an accessory on the bottom shelf and additional gooseneck accessories mounted on top is for illustrative purposes only and forms no part of the claimed design.
